TELESCOPIC LAWN SPRINKLER

Garry H. Shields, Portland, Oreg.

Application November 6, 1950, Serial No. 194,319

2 Claims. (Cl. 299—104)

1

This invention relates generally to sprinklers and particularly to a telescopic lawn sprinkler.

The main object of this invention is to construct a lightweight, inexpensive, portable sprinkler, which can be readily extended from six to twenty-four feet in length, and made to sprinkle from two to twenty feet wide, depending upon the pressure of the water delivered to the sprinkler.

The second object is to provide a unique form of joint whereby the joint is automatically held to a seating position when the joined parts are fully extended.

These and other objects are accomplished in the manner set forth in the following specifications as illustrated in the accompanying drawings, in which

Fig. 1 is a plan of the sprinkler in an extended position.

Fig. 2 is a plan of the sprinkler in a contracted position with portions broken away to disclose the innermost tube.

Fig. 3 is a fragmentary section taken along the line 3—3 in Fig. 1.

Fig. 4 is a fragmentary section taken along the line 4—4 in Fig. 2, showing the last joint and tip end of the sprinkler.

Fig. 5 is an end view of the sprinkler showing the direction of the sprays formed thereby.

Like numbers of reference refer to the same or similar parts throughout the several views.

Referring in detail to the drawing, there is shown a series of telescopic tubes 10, 11, 12 and 13, which are preferably made of a light weight aluminum alloy.

The tube 10 has one end rolled to form a bell end flange 14 within which is a rubber packing ring 15 and threaded hose coupling 16.

Into the tube 10 extends one end 17 of the tube 11. The innermost ends 17 of the tubes 11, 12 and 13 are all constructed as shown in Fig. 3. Each innermost end 17 is rolled out to form a double seat 18 and 19. After the end 17 is inserted in the next larger tube 10, 11 or 12, the outer tube is rolled to form the groove 20 which seats against the seat 19 when the sections are fully extended.

The extreme end of the outermost section 10, 11 or 12 is also rolled in to form the bead 21 which cooperates with the outwardly rolled seats 22 on the outer end of the next smaller tube within to form a seat when two tubes 10 and 11, or 11 and 12, or 12 and 13 are telescoped as far as possible. That is, each tube 10, 11, 12 and 13 has a double seat 18 and 19 at its inlet end and a double seat 22 near its outlet

2

end and has the groove 20 and 21 on opposite sides of the seat 22.

Between each seat 22 and groove 21 is mounted a base 23 which holds the tubing off of the ground and holds all of the sections in a fixed position with relation to the ground 24.

Small holes 25—A are formed in the tubes 10—13, inclusive, through which the water can spray as indicated by the lines 25. A cap 26 holds the tubing in place on its base and is held in place by the screws 27.

All of the sections are alike except for diameter and that the last section 13 is fitted with a plug 28 and a slideable plastic sleeve 29 whose tapered end 30 can be pushed into the space between the outside of the tube 13 and the outer end 31 of the tube 12.

It can be seen that by this construction, the tubes are perfectly sealed in either an extended or a telescoped position.

I claim:

1. A lawn sprinkler consisting of a plurality of telescopically arranged tubes, each tube having a base upon which it rests and adapted to hold it against rotation, all of said tubes having perforations on the upper portion thereof, each adjacent pair of tubes having seals at the end thereof to prevent the escape of water through the joints in the innermost and outermost positions, and a seal on the end of the outermost tube consisting of a plastic ring slidably mounted on said tube having a tapering end adapted to wedge into the space between the outermost tube and the next outermost tube.

2. A sprinkler consisting of a plurality of telescopic tubular members having sealing stops between each pair of members at their innermost and outermost positions of travel, each tubular member having a series of sprinkler holes along one side thereof, bases secured to each section at its outer end in a manner to hold the perforated portions of the tubes uppermost, a lug in the outermost end of the central tube and a conical sleeve slidably mounted on the innermost tube.

GARRY H. SHIELDS.
